SECTION INSULATOR

Arthur J. Knight, Mansfield, Ohio, assignor to
 The Ohio Brass Company, Mansfield, Ohio, a
 corporation of New Jersey

Application May 8, 1943, Serial No. 486,471

14 Claims. (Cl. 191—39)

My invention relates to section insulators for use in sectionalizing trolley wires and refers more particularly to the bridging or runner member of such devices.

One object of my invention is to provide a section insulator in which the bridging member is of a non-combustible insulating material which will withstand the arc produced when a current collector passes from the trolley wire onto the bridging member with current "on."

Another object of my invention is to produce a bridging member having a guiding portion of vitreous material.

Another object of my invention is to produce a bridging member in which the vitreous guiding member is cushioned or protected from vibrations, shocks or jars as much as possible.

Another object of my invention is to provide a bridging member in which the vitreous portion is held in place should it be cracked or broken.

Another object of my invention is to produce a bridging member in which the individual parts of which it is comprised are mechanically interlocked.

Another object of my invention is to provide a bridging member in which the individual parts are united as by cementing.

My invention resides in the new and useful construction, combination and relation of the various parts shown in the accompanying drawing and hereinafter described.

In the drawing:

Fig. 1 is a side view in elevation of a section insulator using my improved bridging member.

Fig. 2 is an enlarged side view of the bridging member in partial section.

Fig. 3 is an end view of Fig. 2.

Fig. 4 is a top plan view of Fig. 2.

Fig. 5 is a section on the line 5—5 of Fig. 2.

Fig. 6 is a section corresponding to that of Fig. 5 but showing a modified relation between the parts thereof.

The runner or bridging member of section insulators have in the past been made of wood, insulating fiber, rubber, etc., but all of these are subject to burning and excessive wear.

By using the guiding portion of the bridging member under proper conditions it may be made of a frangible material such as porcelain, stoneware, glass, etc., especially a boron-silica glass known to the trade as Pyrex.

Such materials being frangible they cannot safely and practicably be used alone as the bridging member since they are subject to more or less pounding, vibration, shock and jars.

Therefore I interpose between the guiding portion of the bridging member and the other parts of the section insulator, means which will absorb such blows, vibrations, shocks, etc. To accomplish this I employ means made of rubber which is either yielding, flexible, resilient or elastic, or any combination of these properties. Rubber is non-metallic and also an insulator.

I may also use as the absorbing means, other material such as any of the so-called synthetic rubbers, or Duprene, neoprene, etc.

In the preferred embodiment of my invention I provide a pair of end members 1 of metal which are held in spaced and insulated relation by the tension member 2 and compression member 3.

The end members are provided with means to receive the trolley wires 4 and which are held in place by set screws 5. Bridging the gap between the end members is a bridging or runner member 6 which guides a current collector from one wire to the other wire. The lower edge 7 of the bridging member 6 is in alignment with the lower or running edge 8 of the trolley wires 4.

The bridging member 6 is secured in place by clips 9, whose lower edges are in alignment with the edges 7 and 8 of the bridging member and trolley wires 4 respectively.

The clips are secured to the end members by securing means 10. By removing the securing means 10, the clips 9 may be removed and this will permit removing or replacing the bridging member 6.

A section insulator of the general type shown in Fig. 1 is more fully described in detail in Patent 2,187,135 issued January 16, 1940.

Referring now to Figs. 2 to 5 inclusive, I have shown in detail the construction of the bridging member 6. This comprises the guiding portion 11 of such materials as described above and the cushioning portion 12 of such materials as described above.

The portion 11 has a lower exposed portion 13 with a contact or running surface 7 for the current collector.

The portion 11 is provided with a part 14 which is slightly shorter than the portion 13 and of less thickness. The cooperating side faces of one or both portions 11 and 12 are provided with serrations, dentations, crenations, etc., which interlock with like or other means on the other portion.

The portion 12 is a holder or receptacle-like part arranged to receive the part 14 of the portion 11. The portion 12 being formed of a yield-

ing, resilient, flexible or elastic non-metallic material, it may be distorted sufficiently to receive the part 14 of the portion 11. The inner side surfaces of the portion 12 is preferably formed in-like manner as that of the portion 11 and thereby securely interlocks with the portion 11 and the portion 12 being yielding, resilient, flexible or elastic or a combination of these properties, it tends to snugly and securely fit the part 14.

The portion 12 is provided with end means which interlock with the clips 19 and is thereby held in position between the end members 1.

In the art of rubber manipulation it is possible to mould into one piece, rubber mixes of different compositions and thereby have different parts of an article possess different degrees of hardness or resiliency, etc., and therefore the end portions 15 may be stiffer than other parts of the portion 12.

The portions 11 and 12 may be formed without the interlocking feature and these parts may be held together as a unit by cementing the adjacent faces together as in Fig. 6 in which 16 is a layer of cement such as is well known to those versed in the rubber and analogous arts.

It is also possible for those skilled in the manufacture of rubber products to vulcanize the portion 12 to the portion 11 under heat and pressure at the time the rubber composition is moulded to shape, by properly preparing the surface of the portion 11 thereby forming a vulcanized surface union. This provides a unitary bridging member in which the portion 11 is not replaceable in case of accidental breakage.

I am aware that my invention lends itself to modifications which will be apparent to those skilled in the art, therefore I wish to be limited only by my claims.

I claim:

1. The combination with a section insulator for a trolley conductor, of a bridging member of insulating materials to guide a current collector across the device, the said bridging member comprising runner part of vitreous material and a casing-like part of flexible non-metallic material which encloses the runner part except for a longitudinal edge portion to contact with the moving current collector and means associated with the casing part whereby the runner part is held in position.

2. The inclusion in a section insulator for a trolley conductor, of a bridging member to guide a current collector across the device, the said bridging member comprising a vitreous part having an edge portion to engage with and guide the current collector and yieldable insulating means enclosing the vitreous part except for the said edge portion and means associated with the bridging member whereby the member is held in position.

3. A section insulator comprising end members, each provided with means to attach a trolley wire thereto, means interposed between the end members to hold them in spaced and insulated relation, and a bridging member of insulating materials interposed between the end members and having an edge aligned with the contact edges of the trolley wires and adapted to be engaged by and guide a current collector from one end member to the other end member, the said bridging member comprising an elongated portion of frangible material and a holder portion of resilient material in which the elongated

portion is positioned with its guiding edge exposed and whereby the elongated portion is supported adjacent its ends.

4. A section insulator comprising in combination end members, each member provided with means to receive and hold a trolley wire end, means interposed between the members to hold them in spaced and insulated relation, and a bridging member interposed between the end members and having an edge adapted to be engaged by and to guide a current collector from one end member to the other end member, the bridging member comprising an elongated portion of vitreous material having its guiding edge aligned with the guiding edges on the trolley wires and a receptacle-like portion in which the vitreous portion is positioned, the last said portion being formed of resilient rubber.

5. A section insulator comprising in combination end members, each member provided with means to receive and hold a trolley wire end, means interposed between the members to hold them in spaced and insulated relation, and a bridging member of insulating materials interposed between the end members and having an edge adapted to be engaged by and to guide a current collector from one end member to the other end member, the bridging member comprising an elongated portion of frangible material having its guiding edge aligned with the guiding edges on the trolley wires and a receptacle-like portion in which the vitreous portion is positioned, the last said portion being formed of a flexible, resilient material.

6. A section insulator comprising in combination, end members, each member provided with means to receive and hold a trolley wire with its lower edge exposed to guide a current collector, means interposed between the end members and secured thereto to hold the members in spaced and insulated relation, a bridging member of vitreous material interposed between the end members and having an edge to receive and guide the current collector, said edge being in alignment with the guiding edges of the trolley wires and insulating means interposed between the vitreous member and the adjacent parts of the section insulator to absorb jars and vibrations and, to protect the vitreous member from injury and whereby the vitreous member is supported.

7. A section insulator comprising in combination, end members, each member provided with means to receive and hold a trolley wire, means interposed between the end members and secured thereto to hold the members in spaced and insulated relation, a bridging member of vitreous material interposed between the end member and having an edge to receive and guide the current collector, said edge being in alignment with the guiding edges of the trolley wires and insulating means interposed between the vitreous member and the adjacent parts of the section insulator to absorb jars and vibrations and the said insulating means being so constructed and related to the vitreous member that in case of breakage of the vitreous member the parts thereof will be held in their normal relation.

8. A bridging member for a line section insulator comprising in combination an elongated portion of vitreous material having an edge exposed to be engaged by and to guide a current collector, a receptacle portion enclosing said vitreous portion except the said exposed edge, the said receptacle portion formed from flexible, resilient or elastic rubber and having means where-

by the bridging member may be secured in position in said section insulator.

9. A bridging member of insulating materials for a line section insulator comprising in combination an elongated portion of frangible material having a longitudinal edge to be engaged by and to guide a current collector, a holder portion formed from resilient material capable of cushioning the vitreous portion and absorbing jar and vibration to prevent injury to the elongated portion and means projecting longitudinally beyond the ends of the elongated portion whereby the bridging member may be secured in position in said section insulator, the said projecting means being formed with less resiliency than the balance of the holder.

10. A bridging member for a line section insulator comprising in combination an elongated bar of vitreous material having an exposed longitudinal edge to guide a current collector, a receptacle of insulating material capable of absorbing vibrations, the vitreous bar positioned within the receptacle except for the exposed edge and means interposed between the adjacent surfaces of the said parts to secure the members together.

11. A bridging member of insulating materials for a line section insulator comprising in combination an elongated bar of vitreous material having an exposed longitudinal edge to guide a current collector, a receptacle-like means of insulating material to receive the vitreous bar and capable of absorbing vibrations, the vitreous bar positioned within the receptacle-like means except for the exposed edge and means on the enclosed faces of the vitreous member cooper-

ating with means on the adjacent face of the receptacle to hold the parts in normal relation.

12. A bridging member for a line section insulator comprising in combination an elongated bar formed of vitreous material having an exposed longitudinal edge to guide a current collector, a holder of insulating material capable of absorbing vibrations, the vitreous bar positioned within the holder except for the exposed edge and means on the elongated bar interlocking with means on the holder to secure the parts in operative relation.

13. A bridging member for a line section insulator comprising in combination a rigid elongated bar formed of vitreous material having an exposed longitudinal edge to guide a current collector, a receptacle of resilient insulating material capable of absorbing vibrations, the vitreous bar positioned within the receptacle except for the exposed edge and means on the elongated bar cooperating with means on the receptacle whereby the parts are normally held together but separable at will.

14. A bridging member for use in an overhead trolley device comprising in combination an elongated bar of vitreous material having an exposed longitudinal edge to guide a current collector, a holder member of resilient insulating material formed by vulcanization and capable of cushioning shocks and vibrations to which the elongated bar may be subjected, the elongated bar being positioned within the holder member except for the exposed edge, the holder being vulcanized to the elongated bar whereby a surface union is formed between the parts.

ARTHUR J. KNIGHT.
